UNITED STATES PATENT OFFICE.

ALICE B. WOOD, OF BEAVER DAM, WISCONSIN.

CORN-POPPER.

SPECIFICATION forming part of Letters Patent No. 240,066, dated April 12, 1881.

Application filed January 25, 1881. (No model.)

To all whom it may concern:

Be it known that I, ALICE BOISE WOOD, of Beaver Dam, in the county of Dodge and State of Wisconsin, have invented a new and Improved Corn-Popper, of which the following is a specification.

The invention consists in a corn-popper formed of two hemispheres of wire work or netting, which are hinged to each other and are provided with a device for locking them together, one of which hemispheres is attached to a rod passing longitudinally through a wooden cylindrical handle, and is provided with an arm at the end for turning the rod, whereby the ball containing the corn is revolved.

In the accompanying drawings, Figure 1 is a longitudinal horizontal sectional view of my improved corn-popper, showing it opened. Fig. 2 is a partial longitudinal view and sectional elevation, showing it closed.

Similar letters of reference indicate corresponding parts.

The two hemispheres A and B, made of any suitable wire-work, are hinged to each other by wires C C or any other suitable hinge. A strong wire, D, passes around the upper edge of the hemisphere B, and this wire forms the rod E, by means of which the popper is rotated.

A wooden cylinder, F, provided with metal washers G G at the ends, is passed over this rod E, and is prevented from sliding longitudinally on the same by the collars H H.

The outer end of this rod or wire E is bent to form a short arm or loop, J. The hemisphere A is provided with a rim, K, which overlaps the edge of the hemisphere B, and has an aperture, L, at its end adjoining the inner end of the rod E. A bolt, M, having a wooden knob,

N, slides on the rod E, between the inner end of the wooden cylinder F and the hemisphere B, and by passing the end of this bolt M into the aperture L of the rim K the two hemispheres A and B will be locked to each other.

The wire D is twisted to form a projecting arm, O, opposite the rod E, to support the ball formed by the hemispheres. The hemispheres may be made of perforated material.

The operation is as follows: The corn is put into the hemisphere B. The hemispheres are then locked together by pushing the bolt M forward, so that the same passes into the aperture L of the rim K. The ball is then placed over the fire, the wooden handle F being grasped with one hand, whereas the ball is rotated with the other hand. The finger can be passed into the loop or ring J, and the ball can thus be revolved very conveniently. The ball can be supported by the projection or arm O, which rests on the edge of the stove. The ball formed by the two hemispheres can be opened without burning or soiling the hands by drawing the bolt M, provided with the wooden knob or button N, backward. The handle F and the rod are to be four or five times as long as the diameter of the ball, so that the person holding the popper need not have his fingers near the fire.

This device can be used over the round opening of a kitchen-stove, the weight being mainly supported by the projection O, which, in this case, rests upon the top of the stove beyond the fire; or the popper may also be used in a parlor-stove.

Having thus fully described my invention, I claim as new and desire to secure by Letters Patent—

In a corn-popper, the combination, with the hinged hemispheres A and B, of the rod E, the wooden cylinder F, the rim K, having an aperture, L, and the bolt M, substantially as herein shown and described, and for the purpose set forth.

ALICE BOISE WOOD.
